UNITED STATES PATENT OFFICE.

AURELIO BAMBINI, OF SEWARD, PENNSYLVANIA.

AEROPLANE.

Application filed October 6, 1925. Serial No. 60,860.

The present invention relates to aeroplanes and aims to provide a novel and improved machine of this character for eliminating accidents caused by the stalling of the engine or accident to the propeller by having a power driven auxiliary propeller arranged on the rear end thereof and adapted to be rotated in an opposite direction from that of the main driving propeller for slowing down the plane in order to land in restricted territories and for use in suspending the plane while descending or for elevating the plane in case of an accident to the main propeller or engine, said auxiliary propeller may also be used if found practical for driving the plane in a rearward direction during flight.

Another object of the invention is the provision of an auxiliary propeller which is collapsible and adapted to be folded against the sides of the fuselage of the plane when not in use, and being arranged so as to be immediately released when desired which will cause the same to be swung to an open position due to the forward movement of the plane, said means for releasing the propeller being connected to the auxiliary engine so as to crank the same for rotating the propeller.

A further object of the invention is to provide the wings of the plane constructed in a single substantial frame, which is pivotally mounted on the fuselage and is adapted to be swung to various positions for elevating or lowering the plane as the same is driven in a forward direction.

It is also an object of the invention to provide an aeroplane of the above indicated character, which is simple and substantial in construction, which can be manufactured at a moderate price, and which will be efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a side elevation of my improved aeroplane, showing the covering for the fuselage removed,

Figure 2 is a top plan of the same,

Figure 3 is a vertical cross section through the forward end of the fuselage, showing the wings in elevation, and

Figure 4 is a fragmentary perspective view of the forward end of my improved plane.

In carrying out the invention, the numeral 10 designates the frame or fuselage of the plane, which is constructed of a series of longitudinal strips 11 which are secured at their forward ends to the radiator 12, at their rear ends to the member 13, and intermediate their ends to an enlarged partition member 14, which will support said strips in the desired formation. About the strips is arranged a covering (which is not shown) for enclosing the interior of the fuselage. Mounted upon the forward end of a pair of the strips 11 is the main engine 15 for driving a propeller 16 mounted on the forward end of the fuselage.

Positioned above and below the forward end of the fuselage are wings 17 and 18, which are braced apart in spaced relation by struts 19 and guy wires 20. Also arranged between the wings 17 and 18 is a bar 21 which has its opposite ends turned up and secured to the upper wing 17, as at 22, said bar 21 extending through the fuselage and being pivotally supported by a pair of the strips 11 forming the frame of the fuselage. Attached to the lower wing 18 and extending upwardly and connected to the bar 21 where the upturned portions 22 are formed are a pair of brace members 23, which connect the lower wing 18 with the bar 21. The bar 21 has an offset portion formed therein so as to provide a crank 24 which has connected thereto one end of a connecting rod 25 that extends rearwardly and has its rear end pivotally connected to a lever 26 pivoted to the frame of the fuselage. By swinging the lever 26 the bar 21 will be rocked, which will either raise or lower the forward portion of the wing members, thus causing the plane to raise or lower in its forward course.

On the upper side of the upper wing 17 is arranged a rudder 28 formed in the shape of a bird, said rudder being mounted on a post 29 extending through the wing 17, which in turn has its lower end attached to a rearwardly extending rod 30. The rear end of the rod 30 has connected thereto the opposite ends of a cable 31 extending through eyes 32 and 33 mounted upon the rear edge of the wing 17. The cable 31 has its inter-

mediate portion wound about a spool or drum 34 carried by a downwardly extending bracket 35 mounted upon the wing 17. In order that the drum 34 may be rotated, I have provided a hand wheel 36 fixed thereto and arranged at a convenient point for operation by the operator of the plane. By turning the hand wheel 36 one end of the cable 31 will be wound upon the drum while the other end is unwound from the drum, thus swinging the rod 30 which will cause the rudder 28 to be swung to either side for guiding the turning of the plane in either direction.

15 Mounted on the frame of the machine in rear of the partition 14 is an auxiliary engine 38 which is provided with an air inlet lever 39 for causing the easy starting of the engine. Extending rearwardly from the auxiliary engine 38 is a shaft 40 which is provided with a pair of universal joints 41 and 42 therein for stepping up the shaft to the center of the fuselage. The rear end of the shaft 40 extends through the rear member 13 of the fuselage and has attached thereto the hub 43 of the auxiliary propeller 44. The auxiliary propeller 44 has the blades 45 thereof pivotally connected to the hub 43 by means of attaching a plate 46 on the inner face of the hub and providing hinge structures 47 at each end of the plate for connection with the blades 45. In order that the blades 45 will be held or retained in an operative position when once swung to such position, I have provided a plate 48 upon the rear face of the hub 43 which has provided at each end thereof and adjacent each blade a pair of spring fingers 49 which are provided with offset portions 50 for engaging over the blades 45 when said blades are swung to an open or operative position.

Extending across the fuselage adjacent the rear end thereof is a bar 52 which has its opposite ends pivotally connected to a pair of the strips forming the frame of the fuselage and has connected to said pivotally connected ends a pair of rearwardly extending extensions 53 which are adapted to engage the outer sides of the blades 45 of the auxiliary propeller for holding said blades in an inoperative position against the sides of the fuselage when the auxiliary propeller is not in use. It can be seen that when the bar 52 is swung on its pivot that the rearwardly extending extensions 53 will be moved out of the path of the blades 45 of the auxiliary propeller, thus permitting said blades to be swung to an operative position due to the forward movement of the plane.

60 Secured to the bar 52 intermediate its ends is an upwardly and rearwardly extending supporting member 54 which supports and carries a rudder 55 positioned slightly above the fuselage at its rear end. The supporting member 54 extends upwardly through a pair of spaced strips 56 arranged upon the rear portion of the uppermost strip 11 forming the frame of the fuselage so that the rudder 55 may be swung upwardly when the bar 52 is swung upon its pivot, thus moving the rudder 55 out of the path of the blades 45 of the auxiliary propeller when said auxiliary propeller is permitted to swing to its operative position, said rudder 55 being swung in its upper position as shown in dotted lines in Figure 1 of the official drawings. A loop portion is formed upon the supporting member 54, as at 57, which has attached thereto the rear end of a cable 58 which extends forwardly and is connected to the air inlet lever 39 and a crank lever 58' connected to the auxiliary engine 38 for cranking the same and to a lever 59 which is pivotally connected, as at 60, to the frame of the fuselage. In order that the above referred to structure will be returned to its normal position, I have provided a coil spring 61 which is attached to the supporting member 54 and to the frame of the fuselage in rear of the supporting member 54.

Mounted upon certain of the strips 11 forming the frame of the fuselage, I have provided rearwardly and outwardly extending metallic members 62 which will form protection for the rear or auxiliary propeller 44. The metallic members carried by the lower portion of the fuselage have provided on their outer or free ends ground wheels 63 which are adapted to support the rear end of the fuselage and prevent the auxiliary propeller from striking the ground should the same be in such a position when landing. At the forward end of the fuselage I have also provided a pair of ground wheels 64 which are supported by struts 65 attached to certain of the longitudinal strips 11 of the fuselage. In advance of the partition 14 I have provided an operator's seat 66 which is arranged at a point where the levers 56 and 59 and the hand wheel 36 are positioned so that the same will be within the easy reach of the operator during the flying of the machine.

In operation, the main engine 15 drives the propeller 16 mounted on the forward end of the fuselage during its flight, the lever 26 controlling the elevating and lowering of the plane while the hand wheel 36 steers the plane from one side to another. When landing it often happens that it is impossible to glide or descend within the space available. In such cases, the lever 59 is moved rearwardly, which will swing the rearwardly extending extensions 53 of the bar 52 in an upward direction, permitting the blades 45 of the auxiliary propeller to be swung outwardly, due to the forward movement of the plane. By connecting the crank lever 58' to the cable 58 said lever

will be swung for cranking the auxiliary engine, thus driving the auxiliary propeller in an opposite direction from that of the main propeller 16. The rotation of the auxiliary propeller can be controlled to either permit the plane to descend slowly or used for elevating the plane, the wings and rudders being used for guiding the course of the plane. It can be seen that when the bar 52 is swung on its pivot that the rear rudder 55 is swung upwardly, so as to not interfere with the turning movement of the blades of the propeller while the same are swinging to their operative position. It is to be noted that the air inlet lever 39 of the auxiliary engine is connected to the cable 58 leading to the lever 59 so that the auxiliary engine will have sufficient air for causing the easy starting thereof. When the blades of the auxiliary propeller are swung to their operative position the spring fingers 49 engage said blades and hold the same in such position until the plane is brought to a standstill, the blades being moved to their inoperative position by the releasing of the spring fingers.

Should it be found practical, the auxiliary propeller may be operated in order to move the plane in a rearward direction. Such movement would be very desirable at certain times during the operating of an aeroplane.

Having thus described my invention, what I claim as new is:

1. An aeroplane having a motor operated propeller comprising an auxiliary motor, a propeller hub connected to said auxiliary motor, propeller blades hingedly connected to said hub so that the blades of said propeller may be folded inwardly when not in use, means for holding said blades in an inoperative position, means for releasing said holding means, a rudder carried on the rear end of said aeroplane, and means for moving said rudder when said propeller blades are released so as not to interfere with said rudder.

2. An aeroplane having a fuselage and motor driven propeller arranged upon the forward end of said fuselage comprising an auxiliary motor mounted in said fuselage, a foldable propeller mounted on the rear of said fuselage operated by said auxiliary motor, a bar extending across said fuselage and being rotatably connected therewith, means carried by said bar for engaging the blades of said foldable propeller for holding said blades in an inoperative position, and means for turning said bar so as to move said means for holding said blades in an inoperative position out of engagement with said blades so as to permit said blades to open.

3. An aeroplane having a fuselage and motor driven propeller arranged upon the

forward end of said fuselage comprising an auxiliary motor mounted in said fuselage, a foldable propeller mounted on the rear of said fuselage operated by said auxiliary motor, a bar extending across said fuselage and being rotatably connected therewith, means carried by said bar for engaging the blades of said foldable propeller for holding said blades in an inoperative position, means for turning said bar so as to move said means for holding said blades in an inoperative position out of engagement with said blades so as to permit said blades to open, and means for holding the blades of said foldable propeller in an open position when said foldable propeller is in operation.

4. An aeroplane having a fuselage and motor driven propeller arranged upon the forward end of said fuselage comprising an auxiliary motor mounted in said fuselage, a foldable propeller mounted on the rear of said fuselage operated by said auxiliary motor, a bar extending across said fuselage and being rotatably connected therewith, means carried by said bar for engaging the blades of said foldable propeller for holding said blades in an inoperative position, means for turning said bar so as to move said means for holding said blades in an inoperative position out of engagement with said blades so as to permit said blades to open, means for holding the blades of said foldable propeller in an open position when said foldable propeller is in operation, a throttle arranged upon said auxiliary motor, and means for opening said throttle when said foldable propeller is permitted to move to an operative position.

5. An aeroplane having a fuselage and motor driven propeller mounted upon the forward end of said fuselage comprising an auxiliary motor, a propeller hub mounted upon said fuselage and operated by said auxiliary motor, propeller blades hingedly connected to said propeller hub, means for holding said propeller blades in an inoperative position and adjacent the sides of said fuselage, means for releasing said holding means, and means for engaging the blades of said propeller when swung to an operative position for holding said blades extended when said foldable propeller is in operation.

6. An aeroplane having a motor driven propeller comprising an auxiliary motor, a propeller hub mounted on the rear of the aeroplane and operated by said auxiliary motor, propeller blades hingedly connected to said propeller hub, and spring fingers mounted on said propeller hub for engaging said propeller blades for holding said blades in an operative position while the auxiliary motor is in operation.

In testimony whereof, I have affixed my signature.

AURELIO BAMBINI.
